UNITED STATES PATENT OFFICE.

CHARLES W. LANPHER, OF NORWICH, NEW YORK.

AUTOMATIC CAR-BRAKE.

SPECIFICATION forming part of Letters Patent No. 253,398, dated February 7, 1882.

Application filed October 18, 1881. (No model.)

To all whom it may concern:

Be it known that I, CHARLES W. LANPHER, a citizen of the United States, residing at Norwich, in the county of Chenango and State of New York, have invented certain new and useful Improvements in Automatic Car-Brakes; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

My invention relates to automatically-acting car-brakes; and the objects of my improvements are, first, to provide a brake of such form as to adapt it to act automatically and independently upon each car of a train to which it is applied, without reference to the other cars of said train, when the speed of the engine is checked, or when it is made to oppose the forward movement of the cars, and to be released by a tendency of the engine to run faster than the cars, such movements being produced by the inward and outward movements of the draw-bars and without any other connections between the cars; second, to provide a novel form of governor to be used, in combination with a pawl and other mechanism, in such a manner that the application of the brakes will occur when the speed of the car is about one mile per hour, or any rated speed at which the governor is set to act, and in such a manner that when the car is drawn at any speed below that at which the governor is set to act the brakes cannot be applied by the inward movement of the buffer, the governor being so arranged with reference to the pawl as to permit the car or cars to be backed at any desired rate of speed without causing the application of the brakes by the inward movement of the draw-bars; and, third, to provide such a construction and combination of devices that the maximum braking force at any time shall be proportional to the combined weight of the car-body and its load, in order that the greatest braking force within the limits of sliding the wheels may be applied, and without causing them to slide upon the rails. I attain these

objects by the mechanism illustrated in the accompanying drawings, in which—

Figure 1 represents in elevation a portion of a car-body resting upon an ordinary truck which is equipped with my improved brake. 55 Fig. 2 is a transverse sectional elevation of a car-body, showing also an end view of the truck, together with a view of the governor and the mechanism for connecting it to the pawl, push-bar, and buffer. Fig. 3 is a detached 60 view, showing the method of constructing the governor and its position upon the car-axle. Fig. 4 is a side-elevation of the spider, to which the arms and weights of the governor are attached. Fig. 5 is a detached view, showing a 65 modified form of the device used in applying the weight of the car-body and its load to the regulation of the force with which the brakes are applied. Fig. 6 is a plan view of the same; and Figs. 7 and 8 are respectively a sectional 70 elevation and a cross-section, showing a modification of some of the parts, which are designed to show their application to iron trucks or to trucks of different construction from those shown in the previous figures. 75

Similar letters refer to similar parts throughout the several views.

In constructing and applying this type of brake I employ substantially the devices shown in the drawings, as well as their combination 80 and arrangement.

A represents one of the sills of a car-body, and B a cross-sill, upon which A rests.

B' is the upper transom, and B'' the lower transom, of the truck. 85

S' S'' are ordinary brake-beams, with shoes attached, and suspended in any of the usual ways.

N is an ordinary axle, to which the governor is attached, as hereinafter described. 90

a a are two pieces of flat iron bolted to the rear end of the draw-bar, or fastened at any other convenient point thereof, and constitute a push-bar. The other end of this push-bar rests upon a bearing between the two arms, 95 near the upper end of the hanging lever c.

Between the bars forming the push-bar a a is pivoted a pawl, b, moving freely about its pivot. One end of this pawl, when in position to apply the brake, drops down in front of the 100

hanging lever *c* and butts against it. When not in position to apply the brake the end of the pawl is raised, as hereinafter described, so that it is clear of the hanging lever *c*, and does not come in contact therewith.

5 Pivoted to one end of the pawl *b* is a connecting-rod, *k*, which is also pivoted to one arm of a bell-crank lever, *k'*, as shown, it being supported in position by an arm, *k''*, projecting from and secured to the upper transom-beam, *B'*, of the truck-frame.

10 To the lower arm of the bell-crank lever *k'* is pivoted a connecting-rod, *l*, which is also pivoted to the upper arm of the rocker-lever *m*, which is supported in position by an arm 15 projecting from and secured to the lower transom-beam, *B''*, of the truck-frame. The end of the lower arm of the rocker-lever *m* is flattened and broadened transversely, and curves slightly 20 ly in a circle concentric with the circumference of the axle. This flat curved end hangs directly in front of the heels of the governor-balls *p p' p'' p'''* as they revolve with the axle.

25 The hanging lever *c* is forked at its upper end from the place where the push-bar *a* arrests, and the two arms are secured at their upper extremities to the car-body, as shown in Fig. 2, its lower end being connected with the upper end of the brake-lever *e* by the rod *d*. The 30 lower end of the brake-lever *e* is connected with the lower end of the opposite brake-lever, *g*, by the rod *f*, and the upper end of brake-lever *g* is connected with the ordinary hand-brake windlass by a rod, *r*.

35 Intermediate between the point of connection of the rod *r* upon the brake-lever *g* and the fulcrum thereof there is connected a rod or chain, *h*, which also connects with the end of the bent lever *i*. The other end of bent lever 40 *i* is pivoted in a casting, *u*, which is secured to the transom-beam *B'*. Near the pivot or fulcrum of said lever is a projecting bearing formed thereon, which is in contact with an iron plate, *w*, the latter being secured to the 45 cross-sill *B* of the car-body.

The governor-balls *p p' p'' p'''* are pivoted in the arms to the collar *o o*, which latter is clamped upon the axle.

50 The action of the brake is as follows: When the car is at rest or is being drawn at a speed of less than one mile per hour, or such other speed at which the governor may be constructed to commence acting upon the brake, the governor-balls drop downward, as they revolve, below a horizontal line drawn through the center of the axle, as shown in the position of the lower ball, *p''*, in Fig. 3. As they continue to revolve and come above the center of the axle they are so shaped that they fall again of their 55 own weight into the position of the upper ball, *p*, of Fig. 3. In this latter position of the balls the heels of their arms come in contact with and force outward the lower end of the rocker-lever *m*, which movement is communicated by 60 means of the rod *l*, bell-crank lever *k'*, and rod *k* to the pawl *b* and turns it, so that it cannot 65 come into contact with the hanging lever *c*.

The draw-bar, and consequently the push-bar *a a*, may at such times be forced inward without producing any effect upon the hanging lever *c*. When the car has attained a speed 70 equal to that for which the governor is set the centrifugal force of the balls permits their falling back into the position of the upper ball, *p*, of Fig. 3, after having assumed the position of 75 the lower ball, *p''*, (shown in same figure,) and thus no contact is formed between the heels of the governor-balls and the rocker-lever, so that the pawl *b* is no longer held in the position as before described, but is allowed to fall in front 80 of the hanging lever *c*. When the draw-bar, and consequently the push-bar *a a*, is forced inward by a retarded motion of the locomotive, the pawl *b* being in contact with the hanging lever *c*, the lever *c* moves backward about its 85 fulcrum, and this motion is communicated by means of the rod *d* and brake-lever *e* to the first brake-beam, *S'*, which is moved until the brake-shoes attached to it are applied to the wheels. The movement of the brake-lever *e* 90 is then communicated by means of the rod *f* and brake-lever *g* to the second brake-beam, *S''*, thereby applying its shoes to the wheels. The force with which the draw-bar is pressed inward is thus communicated to the wheels as 95 a braking force. This braking force may be increased to such a degree that the weight of the car-body and its load, resting upon the before-mentioned projection of the bent lever *i*, is no longer sufficient to hold said lever in its 100 normal position. When this is the case the draw-bar is permitted to move farther inward, the motion being communicated through the hanging lever *c*, rod *d*, lever *e*, rod *f*, lever *g*, and rod *h* to the bent lever *i*, turning the bent 105 lever about its fulcrum in casting *u*, and so lifting the car-body and its load. This movement may continue until the draw-bar has been forced inward to the limiting position of its 110 motion, the car-body continuing to rise slightly, and it is evident that the braking force cannot exceed at any time that at which the car-body begins to rise.

The hanging lever *c*, the brake-levers *e* and *f*, and the bent lever *i* are so proportioned that 115 the lever *i* will begin to move and the car-body to rise when the force upon the wheels through the brake-shoes is only slightly less than the force with which the wheels are pressed upon the rails, so that the greatest permissible 120 braking force is obtained without sliding the wheels, regardless of the weight of the load in the car, and without regard to the greatest limit of the force with which the draw-bar is forced inward. Moreover, this device for limiting the braking force obviates the necessity of 125 any springs whatever in the mechanism to avoid damage by sudden and heavy blows upon the draw-bar, as said bar may move to its limit with any force, and yet the wheels will not slide 130 nor undue strain be brought upon the parts of the brake apparatus. It may be added that as the governor acts alone through the forces due to rotary motion and gravity no springs are

used therein, and no springs enter in any way into the apparatus beyond the buffer-spring always used in cars.

It is not my intention to limit myself to the particular form of the devices employed, especially as regards those used for raising the car-body and its load at certain times, as these may be variously modified, one example of such modification being shown in Figs. 5 and 6 of the drawings herewith presented, where it will be seen that a lever having upon it a series of inclined planes may be used and operated by the same mechanism that operates the bent lever shown in Fig. 1. It is also practicable to use a screw the thread of which is of so coarse a pitch as to produce the desired effect.

It is not my intention to limit my invention to the particular form of levers for communicating motion between the governor and the pawl *b*, as it is obvious that modifications may be made in the lever *m* and in bell-crank lever *k'*, as shown in Figs. 7 and 8, where it will be seen that the lever *m* is changed in form, and that a straight lever is substituted for the bell-crank lever *k'*, neither of such changes making any change in the mode of operation of the device or in the principle, the only object being to facilitate its application to trucks of varying forms of construction.

Having thus described my invention, what I claim, and desire to secure by Letters Patent, is—

1. The combination, in an automatically-act-

ing brake applying and relieving mechanism, of the push-bar *a*, pawl *b*, swinging lever *c*, rod *d*, lever *e*, rod *f*, lever *g*, connecting-rod *h*, bent lever *i*, or its equivalent, and a governor constructed substantially as shown and described, the parts being arranged substantially as set forth, and for the purpose specified. 35

2. In an automatic brake applying and releasing mechanism, the combination of a governor constructed substantially as herein described, a bent lever or equivalent device for raising the body of the car, and suitable intermediate mechanism, the operation being substantially as described. 40

3. The combination, in an automatically-acting brake mechanism, of a pivoted swinging push-bar carrying a pivoted pawl, a swinging pivoted lever for communicating the movements of the push-bar to the brakes, suitable levers and rods for operating the brake-shoes, and a rod, *h*, and lever *i*, the latter being pivoted to the transom-beam of the truck, the parts being arranged for joint operation, substantially as set forth, whereby provision is made for raising the car-body and its load, for the purpose set forth. 50

In testimony whereof I affix my signature in presence of two witnesses.

CHARLES W. LANPHER.
